Des. 175,273
Patented Aug. 2, 1955

175,273

COMBINED SPEAKER ENCLOSURE, RECORD PLAYER, AND RADIO CABINET

Alexander Rauchman, New York, N. Y.

Application September 20, 1954, Serial No. 32,362

Term of patent 7 years

(Cl. D56—4)

FIG. 2

FIG. 1

Fig. 1 is a front elevational view of a combined speaker enclosure, record player, and radio cabinet, as shown and described.

Fig. 2 is a side elevational view thereof;

Fig. 3 is another front elevational view with the compartment doors in open position; and

Fig. 4 is a side elevational view of that shown in Fig. 3.

The rear of the cabinet is of a plain and conventional configuration.

I claim:

The ornamental design for a combined speaker enclosure, record player, and radio cabinet, as shown and described.
